(57) **CLAIM**

The ornamental design for a thin film printer, as shown and described.

DESCRIPTION

FIG. 1 is a front, right, top perspective view of a thin film printer showing my new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof; and,

FIG. 9 is an enlarged view of the encircled area 9 in FIG. 2. The broken lines shown on the drawings depict portions of the thin film printer that form no part of the claimed design. The dot and dash lines indicate the boundaries of the enlarged views depicted in FIG. 2 and form no part of the claimed design.
